(57) **CLAIM**

The ornamental design for set of interlocking beads, as shown and described.

DESCRIPTION

FIG. 1 is a perspective view showing how two similar beads mate together to form set of interlocking beads;

FIG. 2 is a front elevation view of the set of interlocking beads, looking through a hole of the rightmost bead of FIG. 1;

FIG. 3 is a back elevation view of the set of interlocking beads, looking through a hole of the leftmost bead of FIG. 1;

FIG. 4 is a left side elevation view of the set of interlocking beads;

FIG. 5 is a right side elevation view of the set of interlocking beads;

FIG. 6 is a top plan view of the set of interlocking beads; and,

FIG. 7 is a bottom plan view of the set of interlocking beads.
